CLAIM

The ornamental design for a harness buckle, as shown and described.

DESCRIPTION

FIG. 1 is a perspective view of a harness buckle showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the harness buckle where the harness buckle is an open state;

FIG. 10 is a perspective view of the harness buckle where the harness buckle is in a configuration of use; and,

FIG. 11 is another perspective view of the harness buckle where the harness buckle is in another configuration of use. The harness is shown with the symbolic break in its length. The symbolic break lines form no part of the claimed design, and the broken lines in the drawings depict portions of the harness buckle that form no part of the claimed design.
